IMPACT CRUSHER

Edgar B. Symons, Hollywood, Calif., assignor to
Nordberg Manufacturing Company, Milwaukee,
Wis., a corporation of Wisconsin

Application February 10, 1934, Serial No. 710,592

2 Claims. (Cl. 83—46)

My invention relates to crushing machinery and has for purpose the provision of a new crushing mechanism, operating on a new principle and effecting a crushing or breaking down of larger particles to particles of small size with a minimum use of power and a maximum crushing speed and effectiveness. Another object is the provision of a novel impact crusher, whereby material moved along a given course, for example by gravity, is caused to take a substantially instantaneous change of direction by impact. It may thereafter be arrested or caused to take a second change of direction by a further impact, giving two stages of reduction at a single operation. Other objects will appear from time to time in the course of the specification and claims. The present application illustrates a structure adapted for the practice of the process described and claimed in my co-pending application, Ser. No. 710,591, filed February 10, 1934.

I illustrate my invention more or less diagrammatically in the accompanying drawings, where-in—

Figure 1 is a diagrammatic side elevation of 25 the device;

Figure 2 is a plan view;

Figure 3 is a vertical section through the impact portion of the device;

Figure 4 is a horizontal section on the line 4—4 30 of Figure 3;

Figure 5 is a section on the line 5—5 of Figure 3;

Figure 6 is a section on the line 6—6 of Figure 3.

Like parts are indicated by like symbols throughout the specification and drawings.

Referring to the drawings, I show a mechanism embodying my invention. I illustrate generally a device for elevating material, by conveyors or the like, for a free gravitational drop. It will be understood, however, that the propulsion of the material into the impact zone, preferably obtained by a free gravitational drop, may be obtained by other methods or means of propulsion.

Referring to the drawings in detail, A generally indicates any suitable bin or source of supply of the material to be crushed. This indication is intended to be diagrammatic, and material from another conveyor, mine car or the like might be delivered to the device without the intermediary of a bin. For purpose of illustration, however, I illustrate the bin A and a discharge chute or spout A¹, with associated forwardly extending side guide walls A². A³ illustrates any suitable

conveying means for elevating the material to be dropped and crushed. I illustrate it as an endless conveyor passing about a lower pulley A⁴ and an upper pulley A⁵, which may if desired be driven through the drive pulley A⁶ with its belt A⁷ extending to any suitable power source. It will be understood that in this form of my device, material discharged to the conveyor A³ will move in the direction of the arrows upwardly along the conveyor A³ in response to the movement of the conveyor through its closed path. The side walls A² serve to prevent any side escape of the material adjacent the point of delivery from the spout A¹.

As the material passes upwardly along the conveyor A³ it is eventually discharged when the conveyor passes about the pulley A⁵, and drops down the vertical guide passage B. Assuming that a mass of mixed material is discharged down the passage B, with dust, fines and the like mixed in, it may be advantageous, in order to prevent waste of crushing power, to remove some of the fines. I may effect this by any suitable screening along the path of the conveyor A³ but find a practical solution to be the provision of air inlet and outlet apertures in the passage B, whereby a blast of air may be blown across the passage, transversely of the path of drop of the material. This blast of air will carry off a substantial proportion of the dust or fines. I illustrate therefore, an inlet passage B¹, outlet passages B² and air propelling means B³, whereby the fine material may be carried off. It will be understood, of course, that such passages are screened as at B⁴ or provided with mesh of such size that the particles desired to be crushed cannot escape. The use of this preliminary air cleaning in many circumstances is helpful but the crushing method may be used without it.

Assume that the material to be crushed has been dropped by the conveyor or by any other suitable means into the top of the passage B, and that it is falling downwardly through said passage. It will be understood that the passage B may be of such length that the material, if dropped on a fixed surface or anvil, would be moving fast enough to be crushed by the impact of its gravity accelerated drop. However, I obtain a more efficient crushing action by employing a moving impact member provided with one or more impact faces E⁹, the speed of movement and the angle of which, in relation to the drop of the particles, along the passage B, is such as to cause an immediate stoppage and change of direction of the individual particles. This

reduces to a minimum friction or abrasion of the impact surface, which would otherwise be very great, and causes a re-direction of the particles as shown in Figure 3, along a new direction of travel, at the end of which the particles may again be arrested by a second crushing impact against the plates G⁶. It will be understood that whereas preferably the speed of the particles as they move along the passage B is sufficient to cause their crushing or separation upon impact, I may rely only partially or in some circumstances little or not at all, upon the actual drop of the material and, by speeding up the impact member, may obtain a crushing operation by the 10 rotation of the impact member through the falling stream of particles. It will be understood, however, that in the form shown in the present drawings the passage B may illustratively be considered to be of sufficient height to impart to the particles a velocity sufficient to cause their crushing in response to a stoppage at the end of their fall. The stoppage and change of direction causes a very substantial crushing or reduction in size of the particles and the reduced 20 particles are directed in a stream against the second impact member G⁶, where they receive a second impact, and thus are subjected to two stages of reduction in immediate succession.

In the use of my device, the high gravity spout or chute B is an important factor, as it imparts to the falling particles a gravitational speed or acceleration sufficient to carry substantially all of the falling particles into the path of the impact members E⁷. The height of the chute B is so related to the peripheral spacing of the members E⁷ and to the speed of rotation of the rotor, that all or substantially all of the particles are contacted by a full face impact, which prevents, or reduces to a minimum, the glancing blows 40 against the upper edge of the impact members E⁷, which would otherwise prevent the substantially instantaneous and complete change of direction described elsewhere herein and diagrammatically illustrated by the arrows and the stream 45 of particles shown in Figure 3.

Referring to the specific structure for obtaining this result, I provide a housing generally indicated as C, which includes the top portion C¹, the rear wall C², the forward wall C³, and side walls C⁴. C⁵ indicates any suitable lower discharge chute which has an inclined wall C⁶ and if desired an intermediate inclined wall C⁷.

The housing C may be fixed upon any suitable foundation D, as shown in Figure 5, and adjacent the housing are bases or supports D¹ for any suitable bearing systems D² in which rotate the ends D⁴ of the shaft D³. D⁵ is a drive pulley for the shaft D³ which may be in communication with any suitable power source. I illustrate, for example, in Figure 2, the belt D⁶ and the motor D⁷ with its drive pulley D⁸. It will be understood that the shaft D³ may be rotated, at a desirable speed or speeds, by the actuation of the motor D⁷. In order to minimize wear of the bearings and undue strain of the shaft and rotor, I have illustrated in Figure 5 the bearing members D² as being cushioned in rubber sleeves D¹⁵ mounted in split bearing housings D¹⁶. Rotating with and keyed upon the shaft D³ is the 60 rotor hub D⁹. Extending around it is a circular flange D¹⁰ connected to it by the web D¹¹. Outwardly extending from the rim D¹⁰ are a plurality of ribs or projections D¹² which are inclined backwardly from the radius of the motor, 70 in relation to the direction of rotation of the

rotor. They may be strengthened by intermediate ribs D¹³ which appear in Figures 3 and 6.

Secured to opposite sides of the rim D¹⁰ and the transverse ribs D¹² are the side rings indicated as E. These rings may be channeled as 5 at E¹ to receive a corresponding projection from the rim D¹⁰. Each ring is shown as being formed of three separate sections. These sections are secured to the rotor as by bolts E² and tie plates E³. The bolts E² pass through apertures in the 10 rim D¹⁰ or the transverse ribs D¹² and smaller bolts E⁴ pass through the tie plates E³ and the adjoining free end of one of the ring sections E, and are connected at their inner ends with interior wear plates E⁵ as shown for example in 15 Figure 6. The impact plate or plates proper, indicated as E⁷, rest on the forward inclined faces of the transverse ribs D¹². Each plate has a laterally extending lug E⁸ at each side, which lugs are seated in corresponding slots E⁹ in the 20 side plates or rings E. In order to hold the wear plates in place I provide wedges E¹⁰ which slide between the opposed edges of the side ring E as shown for example in Figures 3 and 6. There is a cam or wedge surface E¹¹ against which a 25 corresponding face of the wedge E¹⁰ rides, and a tightening bolt or stem E¹² is provided which may be drawn inwardly as by a nut E¹³, the pin E¹⁴ passing through a boss E¹⁴ integral with the flange D¹⁰. It will be understood that tightening up on the bolt E¹³ will draw the wedge E¹⁰ 30 inwardly along the wedge surface E¹¹ and cause the opposite side of the wedge E¹⁰ to lock against the lug E⁸ of the impact plate E⁷. Not only is the impact plate thus firmly locked, but it is also 35 easily removable for replacement or change. For example, the worn plate may be removed or the angle of the plate may be varied by putting in refill impact plates of varying angle. In such case the wedge E¹⁰ may also be replaced by a 40 wedge of somewhat different shape or contour. In order to prevent material from packing in outside of the side plate or ring members E, I provide a circular flange E²⁰ extending inwardly 45 from each side wall C⁴ of the housing. This structure will be clear for example from Figure 5. In order to provide ready access to the interior of the device I may have one or more removable walls, covers or the like. I illustrate for example, in Figure 3, the side wall portion E²¹ and top 50 wall portion E²², which is hinged as at E²² for ready removal as indicated in dotted lines.

It will be understood that as the material is dropped down the passage B and is engaged by the impact faces E⁷, it is caused to move generally 55 laterally in the direction of the arrows as shown in Figure 3. The particles so delivered are initially crushed at the instant of impact and these smaller particles are delivered laterally at high velocity. I provide an additional breaker plate 60 structure, generally indicated as G, for receiving this high velocity delivery of the smaller particles and for imparting to them, by impact of stoppage, a further crushing or grinding effect. In practice if the material is delivered in sufficient volume and sufficiently steadily down the passage B, the smaller particles will be delivered against the breaker plate structure G at such a speed as to build up something of a mass of material on the forward face of the breaker plate, and the smaller 65 particles will tend to strike this mass of material, causing a very substantial grinding action of particle against particle as well as of impact against the plate proper. In order to effect this result I provide an arcuate supporting wall structure G¹ 70 75

herein shown as of two angular members G^1 hinged as at G^2 for ready removal, cleaning or the like. It is normally held fixed as by the bolts G^3 one end passing through angles G^4 on the housing side wall C^4 . The structure G includes an upper angle G^5 through which the bolts G^3 pass, and which is in connection with the frame proper G^1 . The impact plates proper G^6 , of which two are shown, are bolted to the angle or frame members G^1 for ready removability. It will be noted that the contour of the plate G^6 is generally arcuate, the purpose being to insure that there will be an immediate and complete stoppage of the material received by the plate and no glancing or angular blow. The speed of the rotor is such that all of the material impacted is caught by the impact faces proper E^7 . However, this material, owing to the speed of rotation, is delivered through somewhat varying paths and the impact plates G^6 are curved so that no matter what angle the material may take in relation to its previous travel down the passage B , it will take a path substantially vertical to the opposed portion of the impact plates. In effect the impact plates define an arc the center of which is the face of the rotor impact plate E^7 when it is aligned vertically with the passage B . It will be further understood that as one of the impact plates E^7 passes beyond the line of drop of the material along the passage B another impact plate crosses the stream before any of the material can drop far enough to engage the flange D^{10} . Thus every particle dropped down the passage B is actually caught by one of the impact plates E^7 and is thereby crushed by impact, and the crushed particles are thereby projected against the fixed impact plates G^6 for a further crushing and grinding against the plate G^6 and the mass of material on its surface. In other words, one charge of material delivered by an impact plate does not have a chance to drop away from the face of the plate G^6 before the next charge engages it.

All of the material separated drops down across the inclined surfaces C^8 or C^9 and thus passes from the crusher. Under many circumstances I find it desirable to employ this crusher in closed circuit, to screen out the finer material produced by the crushing operation and to return the oversize for a further crushing. This may be done by a variety of suitable mechanisms and for purpose of illustration, I illustrate but one. I may employ the endless conveyor H passing about the lower pulley H^1 and the upper pulley H^2 . It may be driven for example from the motor H^3 through the belt H^4 and the drive pulley H^5 , pinion H^6 and the gear H^7 . The material delivered from the crusher, in the form of the device shown in Figures 1 and 2, is picked up by the belt H and carried to a distribution member H^8 whence by chutes H^9 H^{10} it may be delivered to screens H^{11} , H^{12} . The oversize from these screens is delivered by discharge chutes H^{13} H^{14} to the up-conveyor A^3 . The screened material may be delivered to a different conveyor H^{15} and thus escape from the crushing circuit.

It will be realized that whereas I have described and shown a practical and operative device embodying my new crushing mechanism, nevertheless I wish the description and drawings herein to be taken as in a real sense illustrative and diagrammatic, rather than as limiting me to the specific mechanism herein shown. Many changes may be made in size, shape, number, and disposition of parts without departing from the spirit of

my invention. For example, the particular conveying or elevating mechanism herein shown may be widely varied, or where the device is not used in closed circuit may even be dispensed with entirely. The air cleaning mechanism whereby fines are drawn or blown from the stream of falling particles may be valuable but is not essential. Also a wide variety of separating means may be employed for separating fines or undersize particles from the material to be crushed. Whereas I have illustrated an impact member of great efficiency, I do not wish to be limited to this precise impact member and it will be understood that great changes may be made in size, shape and also in speed of the impact member. 15

The use and operation of my invention are as follows:

Most broadly stated my apparatus has for purpose to break by impact, particles which are directed or fall into the impact zone, thereby causing the substantially instantaneous stoppage and change of direction of each particle. In the embodiment of my invention herein shown, I move across the stream of falling or moving particles the successive vanes of a rotary impact member. 20 The impact surfaces of these vanes are set at such an angle to the falling stream and are moved at such a speed in relation to the speed of the falling particles as to effect a practically instantaneous stoppage or change of direction of 25 each particle.

Referring to Figure 3, the impact members E^9 are rotated across the path of falling particles and direct them against the impact plate G^6 . Their speed of movement is sufficient to effect a 30 further reduction or breakage at that point. The plate G^6 is curved because the path of movement of the impact directed material from the member E^9 varies in angle as the impact member moves through the falling stream. All the material 35 engages the impact plate G^6 directly, and with no sliding or angling. This being true of the engagement of the particles against E^9 as well as G^6 , abrasion or wear of the plate is reduced to a minimum. The rotation of the shaft D^3 is at 40 such a rate that none of the falling particles can fall through the ring defined by the rotation of the members E^9 without being impacted by one of them. None of the particles can drop down onto the portion D^{10} of the rotor. Furthermore, the successive increments to particles delivered against the plate G^6 may come so rapidly 45 as to build up a species of sheet or mat of material. In other words, the particles which have already been broken by impact against the surface E^9 are directed into the mass of particles resting against or falling across the surface of the plate G^6 . The result is not merely an impact breakage against the plate G^6 but also a grinding 50 of particle against particle which causes a maximum separation important for fine crushing. 55

Whereas my invention may very efficiently be employed in connection with a freely falling column of material, it will be understood that other means of propulsion of the material are possible. 60 For example, the material to be crushed may be allowed to slide down an inclined plate for delivery into the impact zone. Or it may be moved or thrown into the impact zone by other means. The particular details of the mechanism are 65 therefore not to be treated as limitations, except to the extent that limitations are actually written in terms into the claims.

I claim:

1. In an impact crusher a housing, a rotor 75

mounted in said housing for rotation about a generally horizontal axis, said rotor including a plurality of peripherally spaced impact members, means for feeding an unconsolidated stream of particles to be crushed downwardly by gravity, along a defined path into the path of movement of said impact members, adjacent the highest point of their movement, means for rotating said rotor at a speed sufficient to break the impacted particles, the impact faces of said impact members lying in planes parallel with the axis of rotation of the rotor, and being rearwardly so inclined in relation to the direction of feed and speed of feed of the particles, and to the speed of movement of the impact members, 10 as to change the direction of movement of the particles substantially instantaneously when they are impacted and without slippage of the particles across the faces of the impact members, and to propel the impacted particles along paths 15 substantially perpendicular to the faces of the impact members, and entirely out of the path of said impact members, and means for imparting secondary impacts to the particles so impacted, including a fixed stationary crusher plate laterally removed from the rotor and out of vertical alignment with any portion thereof, the effective surface of said stationary plate being normal to the direction of delivery of the impacted particles, and means for carrying off the particles 20 reduced by said secondary impacts along a path remote from the rotor.

2. In an impact crusher a housing, a rotor mounted in said housing for rotation about a generally horizontal axis, said rotor including a plurality of peripherally spaced impact members, means for feeding an unconsolidated stream of particles to be crushed downwardly by grav-

EDGAR B. SYMONS.
